UNITED STATES PATENT OFFICE.

HERMAN SCHLOTHAUER, OF CHICAGO, ILLINOIS, ASSIGNOR TO PYRAMID DRUG COMPANY, OF MARSHALL, MICHIGAN, A CORPORATION OF MICHIGAN.

WRAPPING MACHINE.

Application filed August 2, 1923. Serial No. 655,193.

This invention relates to wrapping machines and has among its objects to provide an automatic machine for wrapping uniform articles.

5 The principal object of this invention is to provide improved means for intermittently feeding and cutting a strip of wrapping paper, and then forming a wrapper of said strip and then loading and sealing the 10 wrapper.

Another object of this invention is the provision of an automatic feeder adapted for containing a quantity of articles and having means for successively feeding one of 15 such articles to the wrapping machine.

A further object of the invention is to provide a wrapping machine having improved wrapper forming means for receiving the cut paper and forming same preliminary to 20 receiving its charge.

Another object finds embodiment in automatic charging means whereby the wrappers are successively charged from the feeder chamber.

25 A further object of the invention is to provide a machine for automatically wrapping material in conical form.

A still further object is to provide novel means for enclosing or sealing the ends of 30 the wrapper after charging.

Other objects will appear from the following description of my invention which is illustrated in the accompanying drawings, and particularly pointed out in the appended 35 claims.

In the drawings, in which like reference characters indicate like or corresponding parts,

40 Fig. 1, is a side elevation of a wrapping machine embodying my invention;

Fig. 2, is a sectional view taken on line 2—2 of Fig. 1;

Fig. 3, is a sectional view taken on line 3—3 of Fig. 1, showing the operating mechanism beneath the platform;

Fig. 4, is a cross section taken on line 4—4 of Fig. 1;

Fig. 5, is a cross section of the automatic feeder taken on line 5—5 of Fig. 6, and

50 Fig. 6, is a plan view of same;

Fig. 7, is an enlarged plan view of the rotary feeder control and device for expelling the imperfect units;

Fig. 8, shows an enlarged view of the

rotary shape-forming spindle for the wrapping and also the charging plunger and feeder loading chamber;

Fig. 9, illustrates the wrapping paper forming rolls and automatic cutter;

Fig. 9^A, shows a plunger device for folding or closing one end of the wrapper;

Fig. 10, shows device for folding the other end of the wrapper and the ejector of the completely wrapped unit;

Fig. 11, illustrates a side elevation of an empty wrapper extractor and

Fig. 12, is a cross section of same taken on line 12—12 of Fig. 11.

Fig. 13 is a view partly in section taken on line 13—13 of Figs. 3 and 14,

Fig. 14 is a detail of the actuating mechanism for the shear blocks; and

Fig. 15 is a sectional view taken on line 15—15 of Fig. 8.

I shall preferably describe my invention 75 as applied to wrapping conically shaped units, such as for instance, medicated cocoa butter cones.

Referring to the illustrations, which show a preferable embodiment of my invention:

A cast iron stand is provided having suitable supporting legs 25 and platform 26. The entire machine is driven by a single motor 27 which is supported on cross supports 28 extending between the rods 29. The main drive shaft 30 carries a gear 31 which is driven by the pinion 32 on shaft 33, which shaft is operably connected to the motor pinion 27^A and gear 34 mounted on the end of the shaft 33. A suitable clutch 35 may 80 be obviously provided for disengaging the mechanism from the constantly operating motor 27.

The wrapping paper 37 is preferably 85 mounted on the spool 36 and is passed under a tightening roller 38 supported on the arm 39 which is pivotably mounted at 39^A. The arm 39 has a depending bracket 39^B which limits the downward movement of the tightening roller 38.

The paper 37 passes over the corner roll 40 and between a pair of feed rolls 41 and 42 which are respectively rigidly mounted to the shafts 43 and 44. The shafts 43 and 44 and the roll 40 are supported in the brackets 45 mounted on the platform 26.

A pair of like gears 46 mounted on the end of shafts 43 and 44 are in mesh and

maintain coaction of the rolls 41 and 42. The shaft 44 carries at its extreme end a ratchet wheel 47 which is rigidly mounted thereto and which ratchet wheel imparts an 5 intermittent rotary motion to the shaft 44 and feed rolls 41 and 42 through the meshed gears 46. This intermittent rotary motion is imparted to the ratchet wheels 47 by means of a pawl 48 which is pivotally 10 mounted to the arm 49.

The arm 49 is cast integrally with the pinion 50 which is loosely mounted on the shaft 44 adjacently to the ratchet 47. The pawl 48 has connection with a small coil 15 spring 51 which extends from it to the arm 49 and which maintains the pawl under resilient pressure in engagement with the ratchet wheel 47.

The pinion 50 and its integral arm 49 receive an oscillating movement through the rack 52 which is slidably mounted in the housing 53 to maintain its constant connection with the pinion 50. The lower end of the rack 52 is extended for pivotal connection 25 to the crank disk 54. The crank disk 54 is fixed on the end of shaft 55 which is supported in bearings 56 and which is driven by a pair of bevel gears 57 operatively connected with the main drive 30 shaft 30.

The upper roll shaft 43 is carried in vertically adjustable bearings 43^A screw-mounted in the tops of the brackets 45.

After the paper strip is intermittently fed 35 from the rolls 41 and 42 it is engaged by the forming rolls 58 and 59. The upper roll 58 is pivotally mounted on the bracket 60 and bears down with its convex periphery into the grooved periphery of the roll 59 40 and so imparts an initial concave formation to the strip of wrapping paper as it is intermittently fed therebetween. The shaft 59^A carries a rigidly fixed sprocket 61 which is driven by the chain 62 extending from the 45 drive sprocket 63 which is fixed to the shaft 44. On the other end of the shaft 59^A is a fixed gear having engagement with a like gear on the shaft 58^A whereby the two rolls 58 and 59 have a uniform coaction.

The casting 64 which supports the rolls 58 and 59 is supported on the supporting bracket 65 and contains a passage 64^A of gradually decreasing diameter into which the arcuately bent strip of paper is fed from 55 the rolls 58 and 59. The casting 64 is provided at its outer end with an enlarged perpendicularly extending integral block 64^B which is provided with vertical grooves 64^C forming guides for the shear blocks 66 60 to which are secured the shear blades 67. The function of the shear blades 67 is to sever the paper strip at even lengths upon its passage from the forming passage 64^A.

The shear blocks 66 reciprocate in opposite 65 directions and are actuated from the main

drive shaft 30 by means of a cam drive which is illustrated in Figs. 13 and 14 and which is employed as a standard for the other units hereinafter specified. This cam drive is also shown in Fig. 4 together with the 70 interconnecting links and cranks for actuating the shear blocks. Referring now to Figs. 4, 9, 13, and 14, the link 68 is pivotally connected at its upper end to a crank arm 69 which is mounted in the bracket 70. 75 At its lower end the link 68 is provided with a slot 68^A to permit the passage of the main drive shaft 30 therethrough. This slotted end is mounted adjacent and between the cam 71 and collar 72. A roller 73 is mounted on the link 68 for engagement by the cam 71 whereby the link 68 is reciprocated to move the end 69^A of the crank 69 upwardly from the position shown in Fig. 4. A spring 74 is provided to act against the cam 85 movement and to thereby always maintain the cam 71 in engagement with the roller 73.

Referring now particularly to Figs. 4 and 9, the upper shear block 66 is pivotally mounted to a crank arm 75 (similar to arm 90 69) which is pivoted at 75^A to the block 64^B and the depending portion of the arm 75 is connected with a link 76 to the end 69^A of the arm 69. The lower shear block 66 is provided with a pin 77 which extends into a slotted opening 77^A within the link 76. It is now obvious that in the upward movement of the links 68 and 76, the lower shear block 66 will move upwardly while the upper shear block will move simultaneously 10 downwardly due to its mounting on the crank arm 75, and in such movement, the conically formed strip of extending paper will be sheared by the blades 67 and sheared conical wrapper indicated by 78 which extended into the retaining member 79 will now be ready to be moved in the rotary disk carrier 80 into loading or changing position.

The rotary disk carrier 80 is provided 11 with six wrapper retaining members 79 which resemble a bolt, having a head 79^A and a nut 79^B, the interior of which is here provided with a conical bore 79^C.

The intermittent operation or rotation of 11 the disk carrier 80 will later be more fully described.

Preliminary to loading or charging of the wrappers, the carrier 80 moves one sixth of a rotation in a clockwise direction shown by 12 arrow in Fig. 4, and thus brings the wrapper 78 from the shearing position into alignment with the rotary shape-forming plunger 81. (Shown enlarged in Fig. 8.) This plunger revolves at a constant relative high speed, and between the next movement of the carrier 80 moves quickly into and out of the aligned wrapper 78, thus definitely setting the conical formation of the wrapper. The plunger 81 is slidably mounted in the bearing 13

82 and is slidably keyed to a revolving end carrying the pulley 83 which pulley is constantly driven by a belt 84 passing over a pair of idler sheaves 85 from the drive pulley 86 which is fixed to the main drive shaft 30. As the plunger 81 is slideable longitudinally within its keyed connection 87 it can readily be quickly moved or reciprocated by a cam 71 on shaft 55 operating the link 68^x, (see Fig. 3, similar in construction to link 68 shown in Figs. 13 and 14 and described above) which link 68^x operates the arm 117 pivoted at 118 to reciprocate the connection 87 through the link connection 119 (see Fig 1).

The next one-sixth rotation of the carrier 80 will bring the wrapper 78 into alignment with the loading chamber shown also in Fig. 8, but before describing this structure I will proceed with the specifications of my improved feeder.

The feeder is illustrated in Figs. 1, 2, 4, 5, 6, and 7, and comprises a cylindrical receiving chamber 88, open at the top to receive a quantity of the medicated cones. A right angular discharge opening 88^A is provided in the bottom 88^B and portion of the side, as shown in Figs. 5 and 6. Laid on the bottom 88^B and within the chamber is an intermittently rotating disk 89 which is fixed to a central shaft 90. The periphery of the disk 89 is provided with equally spaced openings 89^A and the portion between the openings is slightly beveled towards the edge of the disk. The length of these openings 89^A being slightly greater than the length of the cones. The shaft 90 extends through the bottom 88^B and carries a fixed bevel gear 91 which meshes with the bevel gear 92 which is fixed to the shaft 93 the other end of which carries the ratchet 94, which ratchet is intermittently operated by the spring-pressed pawl 95 pivoted on the lever 96 which is also pivotally mounted on shaft 93. The shaft 93 is carried in the bracket bearing 93^A. The lever 96 is oscillated by the connected rod 97 which is fixed to the crank disk 98. The crank disk 98 is fixed to the shaft 99. The shaft 99 is carried on the bracket bearings 100 and is driven by a pulley 103 fixed on the main drive shaft 30.

As the disk 89 rotates clockwise in Fig. 6, the quantity of cones will be moved upwardly in the inclined hopper toward the opening 88^A and to thin or reduce this quantity to a layer whereby the openings 89^A will each receive a single cone for conveyance to the discharge opening 88^A, I provide a pair of rotating brushes 104 mounted on the arm 105 which is keyed to the shaft 106. On the upper end of shaft 106 a gear 107 fixed thereto meshes with gear 108 which is fixed to the shaft 90 for the purpose of receiving intermittent motion. It will be noted that the

chamber 88 is inclinedly and pivotally mounted at 88^C to the supporting bracket 109.

For the purpose of controlling the discharge of only whole or perfect cones to the feeder tube 110 I provide an intermittently rotating drum 111 which comprises a pair of flanges 111^A between which is a cylindrical hollow sleeve 111^B having four equally spaced depressions 111^C to receive the unit cones. The depressions 111^C extend longitudinally of the cylindrical sleeve 111^B and are provided with relatively large openings or slots 111^D extending longitudinally for the greater part of the depression. It is now apparent that if a part of a cone is passed to the drum 111, such part if shorter than the length of the opening 111^D will fall through the sleeve 111^B into the imperfect cone tube 112 for discharge into any suitable separate container which may be placed alongside of the machine.

As a further means of avoiding the passage of any imperfect cone or part of one, I provide the feeder tube 110 with a wire frame body 110^A and just opposite the tube 113, which also discharges into the same container for the tube 112, I crimp or deform one of the lower wires, as at 110^B, which will afford a means of by-passing the small broken parts to the tube 113. The drum 111 is supported on a shaft 111^E extending integrally with and in opposite directions from both flanges 111^A into bearings 114, and at one end of this shaft I secure a drive disk 115 having a plurality of equally spaced pins 116 which extend outwardly into the path of the pivoted end 96^A of the lever 96. The end 96^A is provided with an integral extension or lug 96^B which normally engages the underside of the lever 96 to afford an upward movement of the end 96^A rigidly with arm 96. Referring now to Fig. 4, if the disk 98 is moved anticlockwise, as the lever 96 will be oscillated to move the pivoted end 96^A upwardly and rigidly with arm 96 during its engagement of one of the pins 116 to rotate the drum 111 anticlockwise. In the reverse oscillation of the lever 96, the end 96^A will be moved downwardly, but because of its pivotal support on arm 93, will be swung past the pin 116 which it had previously raised and will after passing same drop by its weight into normal operative position under the next pin 116 into a position to move such pin upwardly on the next upward oscillation of the end 96^A.

It is necessary that each one be dropped into the wire tube with the larger or heavier end of the cone forward and for this purpose I provide depressions 111^F at end of the depressions 111^C which depressions 111^F are arcuate cavities smaller in diameter than the base of the cone but greater than its apex. Thus the apex of each cone will

lodge in same and in the discharge of the cones from the drum 111, the base of the cone will roll out first with the apex lying in the cavity 111^F and will be retarded in its rolling discharge. This arrangement insures the base of the cone rolling or discharging first.

The lower end of the feeder tube 110 is provided with a feeder chamber 120 comprising a cylinder chamber open at the front or discharge side at 120^A. The chamber 120 is fixed to the bracket 65 with a bolt 121, (see Fig. 8). The bearing 122 is also cast integral with the bracket 65 and carries 15 the slideable feeder plunger 123 which is rigidly fixed to the operating sleeve 124 having an integral flange 124^A. The feeder plunger end is slightly beveled at its upper side 123^A and carries a rubber tip 124. 20 The cones slide down the tube 110 to the stop pin 125 which normally extends into the upper part of the feeder chamber to support the lowermost cone. The pin 125 is fixed to a depending member 126 which is 25 rigid on the pin 127. The pin 127 is mounted for reciprocation in the upright supports 128 rigidly mounted on bearing 122. A coiled spring 129 extending between the collar 127^A and upright 128 retains the pin 30 127 in a position with the stop pin 125 extending into the interior of the feeder chamber 120 to support the cones in the tube. The outer end of pin 127 is provided with a forked end 127^B having a slotted opening 35 127^C for the pin 130 which is carried in the upper end of the lever 131 pivotably mounted to the upright 128 at 131^A.

When the feeder plunger 123 moves into loading position as shown by the full lines 40 in Fig. 8, the cone lying in the arcuate extension 122^A is pushed into the aligned wrapper 78 which was brought into such position by the one-sixth rotation of the carrier 80, from its preceding aligned position 45 with the form setting rotary plunger 81 and during the loading movement of the feeder plunger 123, the flange 124^A engages the notched end of the lever 131 thus moving the pin 127 outwardly against the pressure 50 of the coil spring 129 to quickly withdraw the stop 125 to allow another cone to pass down into the loading chamber. The pivotal mounting of the lever 131 is so arranged that the release of cone from the 55 tube 110 is done very quickly and before the next cone would also pass down the pin 125, due to the action of the spring 129, is quickly passed into a stop position to retain it, thus only one cone is fed at each 60 reciprocation of the pin 127. The cone discharged into the feeder chamber 120 is seated in a slightly inclined position with its base on the inclined face 123^A of the feeder plunger 123 and in the reverse or outward 65 movement of the plunger 123 is laid into the

extension 122^A into a proper loading position with its apex forward ready to enter the conical wrapper on the next loading movement of the plunger 123.

To lay the cone down on its side in the 70 extension 122^A I provide a rubber lip 132 which is fixed to the extension 122^A by screws 133 and in such position that the cone resting in an inclined position on the bevel 123^A will be easily tilted off its support. 75

The operation of the plunger 123 and its coacting mechanism is accomplished through a cam 71 on shaft 55, operating the link 68^Y (similar to 68), arm 134 which is pivoted at 135, and the short link 136 connecting the upper end of arm 134 with the sleeve 124. 80

After the cone is loaded into the wrapper, the carrier 80 makes another one-sixth revolution and the loaded wrapper is brought into aligned position with the end folding and sealing reciprocating plunger 137 which is supported in the bearing 138. 85

The outer end of the plunger 137 carries 90 a rigidly mounted sleeve 139 which is reciprocated by the standard mechanism comprising cam 71, mounted on shaft 140 which is driven by a pair of bevel gears 141 from the main drive shaft 30 supported by brackets 142. The cam 71 drives the link 68^Z (similar to 68) which link is connected to the pivoted arm 142, the upper end of which is connected by the link 143 to the sleeve 139. 95

The inner end of the plunger 137 carries 100 a nut 137^A on the end of the integral section 137^B which is of small diameter and a slidably mounted cylindrical head 144 which is formed with a central conical depression 144^A adapted to fit over the head of the retaining member 79. It may here be stated that the mouth of the depression 144^A is wider than the open end of the projecting wrapper, so that the wrapper is gathered together as the mouth of the depression 144^A engages same. Normally the spring 145 retains the head 144 projecting beyond the nut 137^A so that as the plunger 137 is moved forward the conical depression will be the first to engage the open end of the wrapper. 11 The tension or resistance of the spring 145 is sufficient to fold the wrapper into the depression 144^A while upon continued movement of the plunger the head 137^A will engage the folded end of the wrapper to permanently fix or seal same. 11

The next one-sixth rotation of the carrier 80 will bring the loaded wrapper with one end sealed into alignment with the apex sealing mechanism illustrated in Fig. 10. The apex sealing mechanism consists of an oscillating spindle 146 supported in a bearing 147 and having a ratchet wheel 148 at its outer end. The ratchet 148 is operated by a rack 149 having pivotal connected with 12

the rotary disk 150 mounted on one end of the shaft 151, the other of which is driven by a pair of gears 152 from the main shaft 30. On the inner end of the spindle 146, 5 I mount a pair of coacting fingers 153 which are pivotally mounted at 153^A to the parallel side supporting bars 154 which are rigid with the spindle. The ends of the fingers are disposed toward each other as at 153^B to provide means for gripping the projecting apex of the wrapper. To maintain the finger in separated or open position as shown 10 dotted, I provide leaf springs 155 riveted at one end to the spindle and having their free ends exerting pressure against the fingers. A clutch 156 loosely mounted on the spindle and having a conical end 156^A, is arranged to slidably engage the beveled ends 153^C to bring the finger ends 153^B together 15 against the pressure of the leaf springs 155. The operation of the clutch 156 is accomplished by the lever 157 which is pivoted at 158 and the lower end of which is reciprocated by the standard cam mechanism comprising cam 71 actuating the link 68^M. It is now apparent that as the rack 149 oscillates the spindle 146, the fingers 153 are simultaneously brought into engagement 20 with the projecting apex of the wrapper 25 whereby the wrapper's apex is sealed by a twist.

The loaded wrapper now being sealed at both ends is ready to be discharged from its retaining member 79 within the carrier 80.

The discharging mechanism is also illustrated in enlarged detail in Fig. 10 and comprises a plunger 159 having a discharge end 159^A and a supporting bearing 160. A sleeve 161 rigidly fixed to the plunger 159 is connected by the link 162 with the operating lever 163 which is pivotally mounted at 164 and actuated by my standard cam mechanism comprising cam 71 and link 68^N.

The final operation to be described is the actuation of the carrier 80 in its intermittent motion, which as above stated was one-sixth of its complete rotation. The mechanism comprises a ratchet wheel 165 which is keyed to the shaft 166 upon which the carrier 80 is fixedly mounted. Adjacent this ratchet wheel 165, and loosely mounted on the shaft 166, I provide an oscillating arm 167 to which I pivot a spring-pressed pawl 168, 45 which pawl constantly engages the ratchet wheel 165 and upon each oscillation of the arm 167 move the ratchet wheel one-sixth of its complete rotation, thus imparting an intermittent motion to the shaft 166 and carrier 80. The oscillation of the arm 167 is attained by the connecting rod 169 which connects its end with the crank disk 170 mounted rigidly to the end of the main drive shaft 30.

65 Referring to Figs. 11 and 12, the integral

vertically extending block 64^B of the rolls-supporting casting 64 has attached thereto by screws 170^B, a metal plate 170 which extends outwardly toward the carrier 80 and which has the outer end thereof bent at a right angle and provided with saw-like teeth 170^A which are adapted to engage and extract the wrapper 78 which for some reason should not be filled during the operation of the machine; in such instance, for example, 70 as when the feeder should miss depositing a charge.

I claim:

1. In a machine for automatically wrapping conical-like units, a loader comprising 80 a reciprocating plunger feeder, and means for controlling the position of the conical unit during loading by said feeder whereby the unit will be moved with its apex forward.

2. In a machine for automatically wrapping conical-like units, a loader comprising 90 a reciprocating plunger feeder, means for successively feeding the units to said feeder, and means for controlling the position of the conical unit during loading by said feeder whereby the unit will be moved with its apex forward.

3. In a machine for wrapping conical-like units, means for retaining a wrapper, 95 said wrapper being conically formed to receive a conical-like unit, means for loading said wrapper, means for gathering and folding the base of said conical wrapper, and means for twisting the apex of said wrapper 100 to close same.

4. In a machine for wrapping conical-like units, means for retaining a wrapper, 105 said wrapper being conically formed to receive a conical-like unit, means for loading said wrapper comprising a reciprocating member having a cavity with an inwardly converging interior adapted to receive the open base of said wrapper and gradually gather same together and a ram operating 110 at the base of said cavity to fold the gathered end, and means for twisting the apex of the wrapper to close same.

5. In an automatic wrapping machine, 115 means for successively feeding a plurality of units from a common receiving hopper, mechanism for feeding, shearing, and shaping a strip of paper to form hollow wrappers open at both ends, a rotary carrier adapted to receive said wrappers, and mechanisms 120 coacting with said carrier for successively loading, closing the ends of said wrappers, and discharging the wrapped units, said loading mechanism including a plunger adapted to receive a unit in slightly tilted vertical position and on its backward stroke cause a displacement of said unit into a lateral position and on its return forward stroke cause said unit to move into said 125 wrapper.

6. In an automatic wrapping machine, the combination of means for successively feeding separate units from a common hopper; mechanism for intermittently feeding, shaping and shearing a strip of paper to form tubular wrappers open at both ends; an intermittently revolving rotary carrier adapted to receive said wrappers with the open ends thereof projecting on each side of said carrier; means comprising a reciprocating plunger adapted to receive said units and successively load same into said wrappers; means for closing one end of the loaded wrappers comprising a reciprocating plunger having a head slidably mounted thereon, said head having a depressed mouth therein adapted to receive and gather together the open end of said wrapper and being arranged to permit the movement of the plunger therethrough to close the open end of said wrapper by pressure against the gathered end; means for successively twisting the other open end of said wrappers comprising a pair of pivoted fingers mounted on a revolving shaft, said fingers having their rear ends beveled, and an intermittently reciprocating conical member mounted on said shaft and adapted to engage the beveled ends of said fingers to grip the open end of said wrapper therebetween, whereby said wrapper end will be twisted to close same; and an intermittently reciprocating plunger adapted to eject the wrapped unit from said rotatory carrier.
7. In an automatic wrapping machine, the combination of means for successively feeding separate units from a common hopper; mechanism for intermittently feeding, shaping and shearing a strip of paper to form tubular wrappers open at both ends; an intermittently revolving rotary carrier adapted to receive said wrappers with the open ends thereof projecting on each side of said carrier; means comprising a reciprocating plunger adapted to receive said units and successively load same into said wrappers; means for closing one end of the loaded wrappers comprising a reciprocating plunger having a head slidably mounted thereon, said head having a depressed mouth therein adapted to receive and gather together the open end of said wrapper and being arranged to permit the movement of the plunger therethrough to close the open end of said wrapper by pressure against the gathered end; means for successively twisting the other open end of said wrappers to close same; and an intermittently reciprocating plunger adapted to eject the wrapped unit from said rotatory carrier.

In witness whereof I affix my signature.
HERMAN SCHLOTTHAUER.
